CLAIM

What is claimed is the ornamental design for a beverage maker, as shown and described.

DESCRIPTION

FIG. 1—is a perspective view of the new design;
 FIG. 2—is a front view of the new design shown in FIG. 1;
 FIG. 3—is the right side view of the new design shown in FIG. 1;
 FIG. 4—is the left side view of the new design shown in FIG. 1; and,
 FIG. 5—is a top view of the new design shown in FIG. 1. The broken lines in the drawing depict portions of the beverage maker that form no part of the claimed design.
